18 Claims. (CL 158—36)

1 This invention relates to burners for liquid fuel provided with whirl or vortex chambers for atomizing liquid fuel under pressure by discharge through an orifice while rotating. In such burners the fuel is conducted through one or more whirling ports or channels, directed tangentially to the circular whirl chamber, into the whirl chamber near an outer wall thereof and moves in a more or less spiral path toward the center line of the chamber with a progressively increasing angular velocity; the rotating fuel finally leaves the chamber through the spray nozzle orifice in the form of a hollow or annular jet, which is subsequently converted into a conical spray of fuel the apex angle of which is called the angle of atomization.

In such atomizers the quantity of liquid atomized in unit time is proportional to the square root of the supply pressure, i. e., the pressure of the fuel supplied to the whirl chamber. However, unless special precautions are taken, the adjustability range of these burners is small, as the ratio between the largest and smallest quantity of atomized fuel is only proportional to the square root of the ratio between the maximum and minimum supply pressures.

It is an object of the invention to improve the adjustability range of such whirl-type atomizing liquid fuel burners.

It is a further object to improve the adjustability range of such burners by changing the viscosity of the fuel supplied to the whirl chamber while maintaining the angle of atomization substantially constant.

Still another object is to provide a whirl-type atomizing liquid fuel burner having a fuel supply system for changing the viscosity of the fuel concurrently with changes in the supply pressure for increasing the adjustability range of the burner. Another object is to provide a fuel supply system which can change the viscosity in such a way that the angle of atomization is maintained substantially constant over considerable variations in the viscosity of the fuel fed to the burner.

With these and other objects in view, which will become apparent from the following description, reference is made to the accompanying drawings forming a part of this specification and illustrating three preferred embodiments of the invention by way of illustration, and not by way of limitation, wherein:

Fig. 1 is a viscosity-flow rate diagram illustrating the relationship between viscosity, flow rate and supply pressure;

2 Fig. 2 is a diagrammatic flow diagram showing an installation according to the invention wherein variations in viscosity are caused by means of variations in temperature;

5 Fig. 3 is an enlarged, longitudinal sectional view of a whirl-type atomizing nozzle;

Fig. 4 is a diagrammatic flow diagram of a modified installation wherein two liquid fuels of different viscosities are used; and

10 Fig. 5 is a diagrammatic flow diagram of another modified installation wherein gas is admixed to the liquid fuel.

The invention is based upon the phenomenon of pressure atomizers of the whirl-type that, for 15 a given fuel pressure, the rate of flow of atomized fuel through the outlet orifice increases with increasing viscosities up to a certain maximum, after which, if the viscosity is further increased, the rate of flow decreases. This relationship is shown for two widely diverging values of the supply pressure; the curve at the left, marked P_{min} is for a low supply pressure, and the curve at the right, marked P_{max} is for a high supply pressure. In this diagram fuel viscosities, V , are plotted as ordinates and rates of flow or rates of fuel consumption, Q , are plotted as abscissae. The influence of viscosity on the delivery or flow rate of atomizer nozzles has heretofore been discussed; see Transactions, A. S. M. E., July 1939, pp. 373-381.

Without limiting the invention to any theory, and merely for the purpose of facilitating comprehension of the relationship shown in Fig. 1, reference is made to Fig. 3, wherein a whirl-type atomizer is shown, having a swirl plug 6 fitted to the end of a fuel supply pipe 7 by a cap 8, and closed at the rear by a screw plug 9. The swirl plug forms a vortex chamber having a plurality of swirling ports 10 disposed tangentially to the 35 circular peripheral wall of the vortex chamber, and an axial, constricted outlet orifice 11. Fuel supplied through the pipe 7 enters the vortex chamber tangentially at the periphery and liquid spins or swirls about the axis, its angular velocity tending to vary inversely as the radius of swirl. This implies an infinite, angular velocity at the axis of the vortex chamber; this being impossible, an air core, indicated at 12, is formed. The outlet orifice 11 from the vortex chamber is 40 relatively small compared to the diameter of the vortex chamber, and the rotating mass of liquid is forced forwardly by the pressure head towards this orifice. It is thus under the influence of two main forces, one, the translational force 45 which urges the fuel axially forward, and the

other, the centrifugal or spinning component, which tends to make it fly outwards radially directly as it emerges from the restricting boundary wall of the orifice. As a result the fuel actually emerges from the orifice as a tube of liquid which is divergently conical and forms a rapidly thinning film, indicated at 13. This film ruptures or breaks up into fine droplets, indicated at 14, due to the instability of the thin film.

It is the formation of the air core 12 which is believed to account for the extremely low coefficients of discharge obtained with nozzles of this type. Measurements show that the air core tends to increase in diameter as the supply pressure increases, and that it is substantially cylindrical, i. e., of uniform diameter throughout its length within the vortex chamber. A limit to the increase in the diameter of the air core with pressure is imposed by the fact that ultimately, with further increase of supply pressure and, hence, output, the friction losses due to viscosity tend to restrict the angular velocity around the axis to some maximum limit, thus inhibiting further increase in the diameter, and tending to lead to a slight diminution of the angle of atomization as more fuel is forced through the orifice due to the increasing pressure.

The less viscous the liquid, the less is the internal friction, and the greater the swirl velocity of the liquid toward the axis of the vortex chamber. Hence, for a given pressure, low viscosity fuel results in an increase in the diameter of the air core 12, resulting in the efflux through the orifice 11 of a thinner tube of fuel and in a smaller flow rate. With a more viscous liquid the liquid near the axis is retarded to a greater degree by viscous friction with respect to the more slowly rotating liquid, near the periphery; this causes the liquid, in flowing toward the vortex axis, to accelerate angularly at a lower rate than in the case of less viscous liquid. This results in a damped swirl with a lesser centrifugal effect, and smaller air-core diameter, and, hence, a greater rate of flow through the orifice. It should be understood that these effects apply only when the fuel pressure is great enough to impart effective swirl, and at lower pressures the nozzle behaves like a plain orifice and produces less output at increased viscosity.

Reverting to Fig. 1, this effect is illustrated, for example, by points *b* and *c* on curve P_{max} . If the pressure is maintained constant, the rate of flow can be increased from *b*' to *c*' by increasing the viscosity from V_1 to V_2 .

Fig. 1 further illustrates that only a limited range of discharge flow rates can be achieved at a constant viscosity. Thus, at the constant viscosity V_1 , an increase in the supply pressure from P_{min} to P_{max} results in an increase in the flow rate from *a*' to *b*'. It was, according to this invention, found that the adjustability range of such burners can be extended by causing an increase in viscosity simultaneously with an increase in the supply pressure. For example, if the viscosity is V_1 when the supply pressure is P_{min} , the viscosity may be increased along any desired linear or non-linear curve, such as the dotted line *a* to *c*, until the viscosity is V_2 at the higher pressure P_{max} . The rate of oil consumption is thereby increased to *c*', and the resulting adjustability ranges from *a*' to *c*', which is considerably larger than the range *a*' to *b*'.

Another important feature of the invention is concerned with the angle of atomization. It is

generally observed that increases in the viscosity at a given pressure produce large decreases in the angle of atomization. It is, however, desirable to maintain the angle of atomization substantially constant to prevent impingement of drops of liquid against the walls of the combustion chamber incident to an increase of the angle, and/or to avoid flow of combustion air around the fuel cone with resultant poor mixing incident to a decrease in the angle. In accordance with the invention it was found to be possible to select a higher viscosity V_2 for the higher pressure P_{max} such that the angle of atomization is the same or substantially the same as that obtained at the lower viscosity V_1 at the lower pressure P_{min} , e. g., differing only a few degrees. Moreover, the curve *a* to *c* is preferably selected such as to maintain a constant or substantially constant angle of atomization at intermediate pressures and viscosities; adjustment along a straight line as indicated may, for example, be used. By way of illustration, it is possible to select V_1 and V_2 at 5 and 80 centistokes, respectively, while maintaining the angle of atomization constant within a few degrees, e. g., less than 4°, that is, permitting a change in the angle of atomization, measured in degrees of arc, of less than $\frac{1}{4}$ times the ratio of the highest to the lowest kinematic viscosity of the fuel. This is remarkable, since the angle of atomization is reduced as much as 20° when the viscosity is increased from 5 to 80 centistokes and the supply pressure is maintained at a P_{min} of 5 kg. per sq. cm.

It is possible, of course, to effect a still greater adjustability range from *a*' to *d*' by adjusting the viscosity along the curve *a*—*d*; but this would entail a considerable variation in the angle of atomization and is not, for this reason, preferred. It is therefore, desirable to adjust the fuel pressure and the viscosity in mutual dependence, in order to obtain the desired effect: a wide adjusting range with a constant angle of atomization.

The viscosity can be varied in any suitable manner, for instance, by supplying different fuels of different viscosities from different sources when the supply pressure is changed; by varying the temperature; by mixing two or more liquids of different viscosities in varying proportions; and by adding to the fuel various combustible or non-combustible gases soluble therein. Methods and apparatus for regulating viscosity are known, per se, and the invention is not limited to the specific arrangements herein disclosed. It may be noted, however, that whereas the prior viscosity regulating devices sought to maintain a constant viscosity, according to the instant invention the viscosity is increased with increasing pressure.

Referring to Figs. 2 and 3 of the drawing, the installation comprises the atomizing nozzle of Fig. 3 previously described, it being understood that the invention is applicable to burners equipped with any type of whirl-type atomizer, wherein the fuel is fed into a vortex chamber through swirling ports, i. e., tangentially disposed ducts, slots, or channels, formed in the side or end wall or the vortex chamber of swirl discs, vanes, inserts, etc. essentially near the periphery thereof, and discharged from the vortex chamber after angular acceleration through an axial orifice. The invention is likewise applicable to the well known spill return burners, wherein a portion of the fuel fed into the vortex chamber is returned through a spill return line. Fuel is supplied to

the supply pipe 7 from any source, not shown, through a pipe 15 by a steam-powered feed pump 16 and flowed through a heat exchanger or oil heater 17. The fuel oil pressure may be adjusted manually or automatically in response to a thermostat or boiler pressure responsive element (not shown) by means of the steam valve 18. The heater 17 is heated by steam supplied through line 19 provided with control valve 20 which is operated manually or automatically dependent upon the pressure and the temperature of the oil leaving the heater. Automatic operation of the valve 20 may be effected through a pressure responsive element, e. g., a bellows 21 connected by a capillary tube 22 to a pressure vessel 23 with expansible liquid such as alcohol and having a thermostatic well 24 projecting into the supply line 7. Increases in the temperature of the oil in line 7 above an equilibrium temperature cause a rise in the pressure of the liquid within the vessel 23, tending to close the valve 20 to reduce the admission of steam to the heater 17. This lowers the fuel oil temperature, tending to re-establish the equilibrium temperature.

The pressure within vessel 23 is further controlled by a plunger 25 operating an expansible bellows 26 and actuated through a linkage from a spring-biased piston 27 in cylinder 28, exposed to pressure in the line 7 through a capillary tube 29. The linkage includes a slide 30 with a fixed upper pivot 30a and an adjustable lower pivot on a link 31 at the end of a screw 31a, and providing a track for roller 32. Rods 33 and 34 connect the roller axle to pivotal connections on the rod 25 and the piston rod 35. Pressure applied through tube 29 depresses the piston 27 and the rods 35 and 34, thereby urging roller 32 downward along its track; this places rods 33 and 25 under compression distending bellows 26 and increasing the pressure within the vessel 23, and permitting the valve 20 to close to admit less steam to the heater and increasing the oil viscosity. The resulting lower temperature will act on well 24 to decrease the pressure and again open valve 20; but the response is made such that the system comes to an equilibrium at a lower temperature following a rise in the pressure in line 7. The fuel system described is such that the heating decreases according as the supply pressure in the line 7 rises, thereby causing the viscosity of the oil to increase; conversely, the heating increases and the viscosity is lowered as the supply pressure falls. By adjusting the screw 31a the response of the bellows 26 to pressure changes can be adjusted, thereby permitting the control to be adapted to different kinds of oil.

The pressure in line 7 may also be controlled by a by-pass line 36 having a control valve 37 actuated by bellows 38, this line being preferably connected between the pressure line downstream from the heater and the suction side of the pump, as shown. It is then possible to operate the pump 16 at a constant speed and to vary the supply pressure in line 7 by control of the valve 37. Such an arrangement is advantageous particularly in the case of low oil pressures, it being then easier for the oil heater to maintain the speed of circulation; the response of the installation is thereby increased. The by-pass line 36 may, of course, be omitted.

The heating may, of course, be effected by other means than steam, and the heater 17, heat supply line 19 and control valve 20 may be regarded as typifying a viscosity regulator of any other character in which viscosity is regulated by means of

heating agents other than steam, such as a flame, an electric heat generator, hot gases, etc., controlled by a valve or a switch; it may also be regarded as typifying a viscosity regulator having a mixing chamber into which lighter fluid may be delivered by pipe 19 under control of the valve 20. Moreover, it is possible to provide other forms of viscosity regulating devices and control systems therefor. Thus, the viscosity regulator may admit a cooling fluid to increase the viscosity as the pressure rises.

The control by means of heating, specifically described in connection with Fig. 2, is particularly suitable in cases where heat is readily available, as in factories and on ships.

In the installation shown in Fig. 4, the atomizer can be supplied from two reservoirs 40 and 41, containing different fuels of lower and higher viscosities, respectively, by means of separate feed pumps 42 and 43, driven by a common motor 44. The reservoirs may, if desired, be provided with heating coils 45 and 46 for controlling viscosity, e. g., for maintaining a uniform viscosity. If desired, the fuels in reservoirs 40 and 41 may be the same, but maintained at different temperatures to have different viscosities. The proportion of the two fuels in the mixture supplied to the atomizer is controlled by means of a mixture control apparatus comprising a cylinder 47 containing a reciprocable piston 48 which functions as a control valve to cover or uncover ports at the ends of the cylinder. The piston 48 is actuated by a linkage, indicated collectively at 49, constructed like that described for Fig. 2, in response to movement of a spring-biased piston 50 acted on by pressure of fuel in line 7 via capillary tube 51. The piston differs from that according to Fig. 2 in that a rise in pressure in the line 7 raises it, moving the piston 48 to the left.

Low and high viscosity fuels are fed to the cylinder through lines 52 and 53, respectively, provided with check valves 54 and 55, and communicating with the cylinder space through axially displaced inlet ports. The length of the piston 48 is equal to the distance, center to center, between the inlet ports. Outlet ports, located diametrically opposite the inlet ports, are in communication with discharge lines 56 and 57, connected to the supply line 7. It is evident that, with the piston 48 in its intermediate position shown, approximately equal quantities of fuels from the reservoirs 40 and 41 will flow transversely through the cylinder 47 and into supply line 7. To increase the fuel consumption of the burner the motor 44 can be speeded up (as by a rheostat controlling the field coil, not shown), resulting in a higher pressure in the line 7; this causes piston 50 to rise and piston 48 to move toward the left, thereby throttling the flow of low viscosity oil through lines 52 and 56 and increasing the flow of higher viscosity oil through lines 53 and 57. Conversely, slowing down the motor 44 lowers the pressure, moving piston 48 to the right and increasing the proportion of low viscosity oil supplied to the burner.

By adjusting the pivot point of the slide in the linkage the system can be adapted to different kinds of oil of divergent viscosities.

The pressure can also be varied without changing the motor speed by providing by-pass lines 58 and 59 around the pumps, provided with adjustable, bellows-actuated control valves 60 and 61. These valves may be controlled by a common capillary tube 62 to effect simultaneous

adjustment of both valves and avoid upsetting the ratio-control action of the piston 48. These valves are, preferably, of the type having a spring-retained valve head urged to closed or controlled position by springs 63 and 64. The valves serve also as safety by-pass or check valves, to permit return of oil in the event that the piston 48 completely closes off the port at the end of one of the lines 52 or 53.

The modified system according to Fig. 4, involving mixing of different fuels instead of varying the temperature may, for instance, be applied in domestic heating installations.

According to the embodiment shown in Fig. 5, the viscosity of the normally liquid fuel is varied by mixing it with a gas, e. g., liquefied hydrocarbon gas such as propane, which will dissolve in or be dispersed in the liquid fuel, this arrangement being particularly suitable in cases where such gas is available in sufficient quantities, as for instance, in petroleum refineries. The normally liquid fuel is fed from a reservoir 65 via a pump 66, powered by electric motor 67, and flowed through line 68 having a check valve 69 into a mixing chamber 70. The gas is supplied from a gas tank 71 in which it is compressed with the aid of a compressor 72 and liquefied. Gas line 73, fitted with check valve 74 and flow control valve 75, ends in a nozzle 76 within the mixing chamber 70. The resulting mixture is discharged from the top of the mixing chamber to the supply line 7 leading to the atomizer. The valve 75 is controlled by a spring-biased piston 77 acted on by the pressure in the line 7 via capillary tube 78.

When the pressure in line 7 is increased (for example, by increasing the speed of motor 67) the piston 77 is raised, thereby throttling the valve 75 and decreasing the proportion of gas supplied to the mixing chamber and increasing the viscosity of the fuel. Conversely, lowering the pressure permits the piston 77 to descend under the influence of its spring, to open the valve 75 and admit more gas to decrease the viscosity.

The pressure can also be controlled by adjusting a flow control valve 79 in a by-pass line 80, permitting use of a constant speed motor.

In this embodiment it is also possible to provide a linkage between the piston 77 and valve 75, as was described for Fig. 2, to vary the response and adapt the system for fuels of different viscosities. It is also possible to vary the relation between the gas supply and the fuel supply by varying the spring load acting on the piston.

I claim as my invention:

1. Method of operating a whirl-type pressure-atomizing liquid fuel burner having a vortex chamber for increasing the adjustability range thereof comprising the steps of supplying liquid fuel to the vortex chamber of said burner in a direction to cause the fuel to swirl about the axis of the vortex chamber, discharging the resulting swirling fuel through a constricted outlet orifice substantially at the axis of rotation of the swirling fuel, regulating the rate of flow through said orifice by varying the pressure of the fuel in said vortex chamber in the same sense as the desired change in rate of flow, and varying the viscosity of the fuel simultaneously with and in the same sense as the pressure.

2. The method according to claim 1 wherein the variation in viscosity is effected by changing the temperature of the fuel.

3. The method according to claim 1 wherein the variation in viscosity is effected by changing the composition of the fuel.

4. The method according to claim 3 wherein the change in composition is effected by blending a plurality of normally liquid fuels of different viscosities to produce the said liquid fuel supplied to the vortex chamber, and changing the proportion of said fuels to vary the viscosity of the said liquid fuel supplied to the vortex chamber.

5. The method according to claim 3 wherein the change in composition is effected by admixing to a normally liquid fuel, gas which is dispersible in the said normally liquid fuel to produce the said liquid fuel supplied to the vortex chamber, and changing the proportion of said gas and normally liquid fuel to vary the viscosity of the said liquid fuel supplied to the vortex chamber.

6. The method according to claim 5 wherein the gas is a normally gaseous, liquefied hydrocarbon gas.

7. Method of operating a whirl-type pressure-atomizing liquid fuel burner having a vortex chamber for increasing the adjustability range thereof comprising the steps of supplying liquid fuel to the vortex chamber of said burner near the periphery of said vortex chamber and in a direction to cause the fuel to swirl with an angular velocity about the axis of the vortex chamber, discharging the resulting swirling fuel through a constricted outlet orifice substantially at the said axis with an increased angular velocity, regulating the rate of flow through said orifice by varying the pressure of the fuel in said vortex chamber in the same sense as the desired change in rate of flow, and varying the viscosity of the fuel simultaneously with and in the same sense as the pressure.

8. Method of operating a whirl-type pressure-atomizing liquid fuel burner having a vortex chamber for increasing the adjustability range thereof and maintaining a substantially constant angle of atomization comprising the steps of supplying liquid fuel to the vortex chamber of said burner in a direction to cause the fuel to swirl about the axis of the vortex chamber, discharging the resulting swirling fuel through a constricted outlet orifice substantially at the axis of rotation of the swirling fuel, regulating the rate of flow through said orifice by varying the pressure of the fuel in said vortex chamber in the same sense as the desired change in rate of flow, and varying the viscosity of the fuel simultaneously with and in the same sense as the pressure to an extent to maintain the angle of atomization substantially constant at different pressures.

9. The method according to claim 8 wherein the change in the angle of atomization, measured in degrees of arc, is less than about 0.25 times the ratio of the highest to the lowest kinematic viscosity of the fuel.

10. Method of operating a whirl-type pressure-atomizing liquid fuel burner having a vortex chamber for increasing the adjustability range thereof and maintaining a substantially constant angle of atomization comprising the steps of supplying liquid fuel to the vortex chamber of said burner near the periphery of said vortex chamber in a direction to cause the fuel to swirl with an angular velocity about the axis of the vortex chamber, discharging the resulting swirling fuel through a constricted outlet orifice substantially at the said axis with an increased angular veloc-

ity, regulating the rate of flow through said orifice by varying the pressure of the fuel in said vortex chamber in the same sense as the desired change in rate of flow, and varying the viscosity of the fuel simultaneously with and in the same sense as the pressure to an extent to maintain the angle of atomization substantially constant at different pressures.

11. The method according to claim 10 wherein the variation in viscosity is effected by changing the temperature of the fuel.

12. The method according to claim 10 wherein the variation in viscosity is effected by changing the composition of the fuel.

13. A pressure-atomizing liquid fuel burner installation comprising: a whirl-type atomizing burner having a vortex chamber, swirling ports for admitting liquid fuel into the vortex chamber in a direction to swirl therein, and a constricted outlet orifice; a conduit for supplying liquid fuel under pressure to said swirling ports; a viscosity regulator for varying the viscosity of fuel in said conduit; means for varying the pressure of liquid supplied through said conduit; and control means responsive to the pressure of fuel supplied through said conduit for controlling the operation of said viscosity regulator, said control means being arranged to increase the viscosity of the fuel as said pressure is increased.

14. The burner installation according to claim 13 wherein the viscosity regulator comprises means for regulating the temperature of the fuel, and the control means is arranged to increase the temperature of the fuel as the said pressure falls and to decrease the temperature as the said pressure rises.

15. The burner installation according to claim 13 wherein the viscosity regulator comprises a fuel heater, and the control means is arranged to increase the supply of heat to the heater as the said pressure falls and to decrease the supply of heat as the said pressure rises.

16. In combination with the burner installation according to claim 13, a plurality of sources of fuels of different viscosities; and means for mixing fuel from each of said sources and supplying

the resulting mixture under pressure to said conduit, the viscosity regulator comprising means for varying the proportion in which said fuels are mixed, and the control means being arranged to increase the proportion of less viscous fuel as the said pressure falls.

17. In combination with the burner installation according to claim 13, a source of normally liquid fuel; a source of normally gaseous fluid; means for mixing said gaseous fluid with said normally liquid fuel and supplying the resulting mixture to said conduit, the viscosity regulator comprising means for varying the proportion in which said normally liquid fuel and normally gaseous fluid are mixed, and the control means being arranged to increase the proportion of the normally gaseous fluid as the said pressure falls.

18. A pressure-atomizing liquid fuel burner installation comprising: a whirl-type atomizing burner having a vortex chamber, swirling ports for admitting liquid fuel into the vortex chamber near the periphery thereof in a direction to swirl therein about the axis of the chamber, and a constricted outlet orifice substantially at said axis; a conduit for supplying liquid fuel under pressure to said swirling ports; a viscosity regulator interposed in said conduit; means for varying the pressure of liquid supplied through said conduit; and control means responsive to the pressure of fuel supplied through said conduit for controlling the operation of said viscosity regulator, said control means being arranged to increase the viscosity of the fuel as said pressure is increased.
